Term of patent 14 years

(Cl. D61—1)

FIG. 1

FIG. 2

FIG. 3

FIG. 4

FIGURE 1 is a front perspective view of a strip storage holder showing our new design;

FIGURE 2 is a right-end elevational view thereof, on an enlarged scale;

FIGURE 3 is a cross-sectional view thereof on the same scale as FIGURE 2 and taken on line 3-3 of FIGURE 1;

FIGURE 4 is a bottom plan view thereof on the same scale as FIGURE 2 and showing a portion of the strip storage holder broken away for convenience of illustration.

The side not shown is substantially a mirror image of the side shown in FIGURE 1.

We claim:

The ornamental design for a strip storage holder, as shown and described.
